UNITED STATES PATENT OFFICE.

ROCKY C. GANGEWERE, OF SELMA, ALABAMA.

SLAG-HANDLING APPARATUS.

1,091,828.

Specification of Letters Patent. Patented Mar. 31, 1914.

Application filed November 14, 1910. Serial No. 592,351.

To all whom it may concern:

Be it known that I, ROCKY C. GANGEWERE, a citizen of the United States, residing at Selma, in the county of Dallas and the State of Alabama, have invented a new and useful Improvement in Slag-Handling Apparatus, of which the following is a specification.

This invention is an improvement over the device for which Letters Patent was granted to me June 14, 1910, No. 961,602.

The object of the improvement is to further decrease the amount of water consumed in the process of cooling, granulating and delivering slag direct from a furnace to a car, and also to eliminate certain features found not to be essential.

In carrying out the invention I employ a sloping chute into which the furnace slag is thrown and down which the slag travels to a curved incline which I now form hollow and into which water is discharged, the hollow incline discharging directly into a car, or, where the location does not permit of direct discharge to the car, upon a conveyor which carries the slag to the car.

In order to obtain the results aimed at my invention consists of the novel features of construction hereinafter described, pointed out in the claim and shown in the accompanying drawings, in which:

Figure 1 is a perspective view of the invention. Fig. 2 is a cross section through the hollow incline. Fig. 3 is a side elevation, showing the lower portion of the incline, and illustrating a conveyer for carrying slag to a car. Fig. 4 is a longitudinal section.

In these drawings 1 represents a hollow, curved incline preferably formed of corrugated metal, to which leads a chute 2. The

bottom of the incline 1 registers at the top with the floor of the chute 2 so that the incline receives the slag. The incline is provided with a suitable supporting frame 3 and the chute has sides 4 to prevent slag from leaving the chute at the sides. The chute widens as it approaches the incline in order to spread the slag thinly over the same. Water is discharged into each side of the hollow incline through pipes 5 and suitable discharge outlets 6 are provided to drain off the water. At its lower end the incline discharges into a car 7.

If the conformation of the ground does not permit immediate discharge to a car a conveyer 8 of any kind may be interposed between the incline and the car.

I have found that by constructing the incline as above the minimum amount of water is required in handling the slag, and this is a matter of importance as furnaces are not always so located that water can be had in such quantities that its conservation is a matter of no importance.

What I claim is:

The combination with a chute, of a hollow longitudinally curved incline formed of corrugated metal, said incline being open at both ends and having the bottom of its upper end in alignment with the chute, means for admitting water through the sides of said incline at points adjacent the bottom member of the incline, and means for discharging water through the sides of the incline at points adjacent the top member of the incline.

ROCKY C. GANGEWERE.
